BOTTLE

James R. McCollum, Downey, Calif., assignor to Glass Containers Corporation, Fullerton, Calif., a corporation of California

Filed Mar. 23, 1962, Ser. No. 69,396

Term of patent 14 years

(Cl. D58—9)

FIG. 1 is a perspective view of a bottle embodying my new design, which view shows the front of the bottle containing a panel, the back being the same as the front thereof;

FIG. 2 is an elevational view of one side thereof the other side being the same;

FIG. 3 is a top plan view thereof; and

FIG. 4 is a bottom plan view thereof.

I claim:

The ornamental design for a bottle, substantially as shown and described.
